UNITED STATES PATENT OFFICE.

ALBERT PIAT, OF PARIS, FRANCE.

BURNER.

SPECIFICATION forming part of Letters Patent No. 761,604, dated May 31, 1904.

Application filed February 17, 1903. Serial No. 143,872. (No model.)

To all whom it may concern:

Be it known that I, ALBERT PIAT, constructing engineer, of 85 Rue St. Maur, in the city of Paris, Republic of France, have invented 5 new and useful Improvements in and Connected with Burners Applicable to the Furnaces Used in the Metallurgical Industry, which improvements are fully set forth in the following specification.

10 The present invention relates to a combined ventilator and mixer intended for feeding heavy hydrocarbons to burners applicable to furnaces generally and particularly to metallurgical furnaces. In this ventilating and 15 mixing device the air and hydrocarbon are mixed by means of a turbine with blades, which is driven by air from a blast-engine and in the center of which the inlet-pipes for the hydrocarbon have their opening. The regulation 20 of the motive current or stream of air and of the subjacent current or stream of air passing to the burner is effected by valves of a suitable gearing. The air feed and mixing 25 device can be set in motion and stopped instantly and certainly by merely opening or closing a cock placed in a suitable position. Finally, the angle which is formed with the vertical branch of the blast-engine by the inlet-pipe 30 opening to the furnace which succeeds the chamber of the turbine is equal to one hundred and twenty-eight degrees as being the most suitable angle at which the atomized liquids should be sprayed with regard to the vertical. This improved mixing and ventilating 35 device is shown in the accompanying sheet of drawings, illustrating one embodiment of my invention, wherein—

Figure 1 is a vertical section, partly in elevation, through the axis of the entire apparatus; and Fig. 2 is a vertical section through the axis of the turbine of the mixing-chamber. Fig. 3 is a perspective view of the means for governing passage 2.

40 As may be seen from the drawings, the air coming from the ventilator, with which every foundry is provided, enters through branch 1 of the general air-conduit. This branch, the axis of which is vertical when the apparatus 45 is in position, is divided up at its lower part

into two portions 2 and 3 by a longitudinal fixed partition 4. Each of the passages 2 and 3 can be made large or small or can even be completely closed by means of a separate arrangement hereinafter described.

55 The adjustment of the opening 2, through which passes the subjacent current of air going to the burner, is effected by means of the following arrangement, constituting, in effect, a valve, to wit:

A movable bottom of three surfaces 5, 6, and 7, jointed together at the points 8 and 9 and joined to the walls of the branch pipe at 10 and 11, is supported by a double-branched lever 12, adapted to rotate round a fixed axis 13, mounted on the walls of the branch pipe. The two branches or arms of this lever are joined to the parts 6 and 7 at the point 9. At one extremity of the axis 10, upon which part 5 is fixed, there is keyed a gear-wheel 14, 70 placed outside the branch pipe, the wall of which is traversed by said axis 10. This wheel engages with a small pinion 15, rotating on a fixed axis 16, said pinion being keyed to a handle 17.

75 As will be seen, the position of the parts 5 and 6 can be altered to open or close passage 2, by reason of the slot in the end of part 7, through which the pin 11 passes. Finally, the handle 17 moves along a guide-slot, in 80 which it can be rendered stationary by means of a bolt to 17', fitted with a thumb-screw. (Not shown). When the passage has been regulated in this manner, an invariable working of the apparatus is obtained, even in 85 spite of any vibrations transmitted by the burner itself or by adjacent apparatus. The operation of such a feed-passage is readily understood. By a slight movement of the handle 17 the operator can either cause the 90 approach to or complete removal from the fixed diaphragm 4, over which the stream of hydrocarbon passes, of the surface 5, which governs the volume of the current of air. It must, furthermore, be observed that this arrangement which assures the rapidity of the operation of closing or opening section 2 also insures its precision. In fact, the relative size of the pinion 15 and the wheel 14 may be so varied that the operator attending to the 100

burner is able to make the surface 5 approach or recede from the diaphragm 4 by slightly moving the handle 17. The extreme position of this surface 5, which corresponds to the 5 complete closing of the opening 2, is shown by the mixed lines in Fig. 1.

The regulation of opening 3, through which there passes the motive current of air acting upon the turbine hereinafter described, is effected in the following manner: A sheet-iron sliding valve 18, mounted in longitudinal guide-grooves 19, has two racks 20 fixed to it, by means of which the plane of its position can be changed. The sliding valve and 15 its racks form one single piece adapted to be operated by pinions 21, keyed on an axis 22 and rotating in bearings made integral with the sides of the burner. The same axis has keyed upon one of its extremities a handle 23, 20 which moves along a slot 24, at any point whereof it can be stopped, and notably at the point indicated in the drawings, by means of bolts 25, fitted with a thumb-screw. (Not shown.) This slight movement assures at 25 the same time the degree of rapidity desired for operating the sliding valve 18, the precision necessary for regulating the working of the apparatus, and, finally, the stability of the sliding valve when it has been placed 30 in the position intended to produce a certain result.

The rapidity in the working of the mechanism for regulating the thickness of the stream of air lying beneath the current of liquid and the adjusting of the sliding valve controlling the quantity of air actuating the turbine result from the improvements which have just been described.

The bladed turbine or atomizer 26, which is 40 put in motion by the motive current entering through the opening 3, is mounted on bearings in the walls of the mixing-chamber 27 and receives on its blades and in its center, as will be hereinafter described, the heavy oil arriving 45 through the unions 28, connected to the pipes which supply the hydrocarbon. The manner in which this turbine is placed in the space left by the sides of the chamber 27 is characteristic. Instead of the clearance between the blades of the turbine and the walls of the chamber 27 being reduced to a minimum it is only reduced from point 29 to point 30. From point 30 up to the sliding valve at the point marked 31 it increases and acquires 50 a spiral form. Upon this part of the wall there are placed at intervals projections 32, 33, 34, and 35 of a determined length and regulated or adjusted in such a way that each molecule thrown upon them by the corresponding 55 blades may be hurled forcibly by the projections upon the wall and thence back upon the turbine-blades, as shown by mixed lines in Fig. 1.

If the course of a molecule be followed by 65 way of example, it will be seen that a molecule

quitting the turbine at point 36 strikes such a projection or rib as 34 at point 37, then impinges violently upon the walls at 38, and from there is projected in the form of spray upon the center of the turbine. If, perchance, this molecule were not sufficiently atomized, it would be caught up again by the succeeding blade of the turbine, which would assuredly reduce it to the form of spray. The result of this arrangement is to prevent the molecules which are thrown against the walls of the chamber in which the turbine moves from remaining attached thereto by reason of centrifugal action until the thick coating that would be formed becoming so large that it would be carried along by the turbine in the shape of a liquid sheet to the furnace. It would then come to pass that this quantity of liquid awaiting ignition in order to be brought up to a sufficient temperature there would periodically occur in the hearth a kind of explosion followed by a thick smoke, the sign of a cooling off in all the heated parts. Such a disadvantageous phenomenon cannot occur with the arrangement that has just been described. 70 Another and equally important characteristic of this turbine lies, as has been stated, in the manner in which the hydrocarbon is brought in contact with the blades. As may be seen from Fig. 2, the blades are cut in such a way as to admit of the entrance of the ends 39 of the hydrocarbon-supply pipes 28, the hydrocarbon thus being poured out at the very center of the turbine, upon the blades of which it is distributed in the form of a large sheet. In practice this is the very best point in order to obtain a perfect mixing. It is quite evident that the passages which admit of the entry of the pipes 39 are made in such a way as to leave as little clearance as possible between these pipes and the sides of each blade. Now in order to admit of the complete stoppage of the burner and in order after the termination of each operation, which consequently necessitates the stoppage of the burner, that it may not be necessary to regulate the sliding valve of the turbine and the feed-passage anew in order to commence a new operation an arrangement has been provided assuring the total and instantaneous stoppage of the burner without 80 first having to manipulate the feed-passage and the slide-valve. This arrangement consists in interposing between the ventilator and the apparatus which is to be heated a cock 40, which completely shuts off the hydrocarbon-spraying pipe 41. On the other hand, it also enables this pipe to be opened to the full in order to avoid all causes for the condensation of the atomized hydrocarbon molecules. To 90 this end the plug of the said cock has surfaces which correspond bur for bur with those of the pipe. It is readily seen that on manipulating this cock 40 it will be possible to stop the apparatus or set it in motion again instantaneously without having to disturb the slid- 95 100 110 115 120 125 130

ing valve 18 or the feed-passage lever mechanism 5 6 7. The advantage that can be realized by being able to completely stop at any desired moment the hydrocarbon coming from the pipe (this stoppage being quite certain, as has been set forth) is as follows: The metal under treatment in a metallurgical apparatus having arrived at the desired liquid condition is ready to be poured into the molds. The burner is stopped; but the very high temperature existing in the furnace placed in operation is gradually communicated to the spraying-pipe 41. At this moment the slightest current of air going in the direction of the burner can cause the ignition of the liquid residue covering the interior of the apparatus. The combustion which would result from such a phenomenon would destroy all the parts which compose the burner. The cock 40 being closed at the moment of stoppage, the causes of such an accident would be done away with. This cock must be constructed of metal throughout that is able to withstand very high temperatures without losing its shape.

Another characteristic of my improved device is the arrangement of the spraying-pipe 41 at an angle of one hundred and twenty-eight degrees to the air-supply pipe 1. The value of this angle is far from being indifferent as regards the reduction of the hydrocarbons into spray and their rapid spraying into the furnace. The effort which forces the liquid molecule thrown out in the form of spray would doubtless conduct it to the point that has been mentioned if the weight did not tend to make it deviate. The change which takes place from the fact of this weight in the initial direction of the molecule can cause it to come in contact with an obstacle, and thus cause its condensation.

The experiments made have shown that the best result is obtained when the angle formed by the axis of the spraying-pipe with the vertical axis of the air-feed is that of one hundred and twenty-eight degrees, hereinbefore mentioned.

Finally, in order to prevent unforeseen accidents resulting from faulty construction causing condensation in the spraying-pipe and in order to prevent anything from reaching the burner that is not a vapor of atomized hydrocarbon a reservoir 42, with a purging-cock 43, has been added to the lower part of the sprayer 41. Particles of hydrocarbon that have liquefied through some unknown cause (a crack, for instance, due to a faulty adjustment or else condensation produced in certain undesirable spaces) become attached to

the lower wall of the spraying-pipe and tend to run along this surface to the hearth; but they come to the reservoir 42, where they are collected and from which they are afterward drawn off by means of the purging-cock with which it is fitted.

What is claimed is—

1. In a mixing device for hydrocarbon-burners, a mixing-chamber, a turbine-wheel located in said chamber, means for delivering hydrocarbon on said turbine-wheel, projections arranged on the wall of said chamber, and means for revolving said turbine-wheel to project the hydrocarbon therefrom against said projections and back again onto the turbine-wheel until the hydrocarbon is completely atomized.

2. In a mixing device for hydrocarbon-burners, a turbine-wheel, a mixing-chamber having a wall which recedes from the blades of said turbine-wheel, projections of different lengths arranged on said wall, means for delivering hydrocarbon on said wheel, and means for revolving said wheel to project the hydrocarbon therefrom against said projections and back again onto the wheel until said hydrocarbon is atomized.

3. In a mixing device for hydrocarbon-burners, a mixing-chamber, a turbine-wheel located in said mixing-chamber, cut-away portions formed in the blades of said wheel, a hydrocarbon conduit or pipe leading into said cut-away portions to conduct the hydrocarbon to the center of said turbine-wheel.

4. In a mixing device for hydrocarbon-burners, an air-conduit divided into two passages, and means for regulating the current of air passing through one of said passages and comprising a slide-valve, a rack fixed thereto, an actuating-handle and connections between said handle and rack whereby the regulation of said slide-valve is effected.

5. In a mixer for hydrocarbon-burners, an air-conduit divided into two passages, a turbine actuated by a current of air traversing one passage, and a valve in one passage for controlling the passage of air therethrough, said valve comprising a plurality of jointed surfaces adapted to be moved into position to vary the size of or to close said passage.

In testimony whereof I have signed this specification in the presence of two subscribing witnesses.

ALBERT PIAT.
